UNITED STATES PATENT OFFICE.

HUGH WALLACE AITKEN AND WILLIAM MACKIE, OF GLASGOW, SCOTLAND.

ROLL FOR SUGAR-CANE MILLS.

No. 871,018.

Specification of Letters Patent.

Patented Nov. 12, 1907.

Application filed April 2, 1907. Serial No. 365,937.

To all whom it may concern:

Be it known that we, HUGH WALLACE AITKEN and WILLIAM MACKIE, subjects of the King of Great Britain and Ireland, and residents of Glasgow, Scotland, have 5 invented a certain new and useful Improved Roll for Sugar-Cane Mills, and of which the following is the specification.

Hitherto certain rolls having figured surfaces have been used in connection with sugar-cane mills—one 10 type having zig-zag ridges and channels arranged axially upon it, there being in this case a pair of intermeshing figured rolls; another type having series of serrations arranged axially, of comparatively narrow width, "breaking joint" or staggered with each other, 15 and so forming a series of substantially rectangular pockets—this form being used in conjunction with one or more plain rolls.

The object of these rolls is to split and effectively crush the cane; the first mentioned form is effective 20 in these matters, but fails in that it does not allow free escape of the juice exuded during the nip which is therefore re-absorbed by the cane upon its being freed from the nip. The second form, while permitting free escape of the juice, fails in that it does not 25 split the cane except at those points in its surface where there are projections—the cane is not, or rather the greater part of it is not, sufficiently broken during its passage between the rolls.

This invention has for its object to provide an improved form of roll for use in conjunction with a plain 30 roll or rolls and which while permitting free escape of the exuded juice before it can be re-absorbed by the cane also effectively splits and crushes the cane.

According to the invention, the roll has formed upon 35 its surface series of short ridges or projections arranged at substantially 45 degrees to the axis and each series at right angles to the adjacent ones. The ridges do not abut, and thus by them there are formed a series of open-ended channels at substantially 45 degrees to the axis and 90 degrees to each other from the ends of 40 which the juice may pass freely; while because the ridges are unbroken across the face of the roll—that is to say at every circumference there are ridges which the cane is bound to encounter—it is thus effectively 45 split, broken and crushed.

It will be seen that the ridges form what may be termed series of tetrahedroid figures, the ends of which are triangular while the sides are trapezoidal figures, two sides of which are parallel and diagonally opposite 50 pairs of angles of which are equal to two right angles. Each series of these figures is at an opposite inclination to the axis of the roll.

Alternatively, two adjacent sides of a pair of oppo-

sitely angled figures may be joined, that is to say, merged into an L-shaped figure.

55

Various arrangements of the novel figuring are shown upon eight accompanying sheets of drawings, each view being an elevation to some extent diagrammatic of a portion of a roll having the novel tetrahedroid figuring which is the subject of the invention.

60

In the example shown in Fig. 1, one series, A, of the tetrahedroid figures at an inclination in the one direction are inter-tesselated with the other series, B, of opposite inclination.

In the example shown in Fig. 2, pairs of oppositely 65 inclined figures, A, B, merged into single L-shaped figures at their adjacent ends and arranged in the one direction, are inter-tesselated with like figures, C, D, merged similarly but arranged in the opposite direction.

The example shown in Fig. 3, differs from the last 70 only in that the figures, A, B, and the figures, C, D, intermesh in opposite hand.

The example shown in Fig. 4, again differs in that the opposed figures are not completely inter-tesselated, plain rectangular spaces, E, being left between them, 75 that is to say instead of as in the two preceding examples the figures being in echelon they are in line.

Fig. 5, differs in showing an example with the spaces, E, but in which there is only the one series of joined figures, C, D.

80

Fig. 6, differs from Fig. 4, in that in its example the ends of the figures are prolonged to fill the rectangular spaces (E) of the former example which do not here appear.

In the example shown in Fig. 7, series of tetrahedroid 85 figures, C, are arranged at one angle, abutting on all sides with one another but preferably breaking joint as shown. With the ends of this series there abuts the ends of a second similar series, D, of opposite angle, the abutting members in alternate rows forming the 90 L-shaped figures previously described. There may be only the two series in the width of the roll or as many alternate series as desired may be used,—Fig. 8, shows an example of this last, the alternating series in this case being of the width of but one figure.

95

What we claim is:—

1. A crushing roll for sugar cane mills having upon its surface figures tetrahedroid in form, their ends triangular, their sides trapezoidal, arranged at equal and opposite angles to each other.

100

2. A crushing roll for sugar cane mills having upon its surface figures tetrahedroid in form, their ends triangular, their sides trapezoidal, arranged at equal and opposite angles to each other and so that the ends of each figure abut upon the sides of adjacent figures.

105

3. A crushing roll for sugar cane mills having upon its surface figures tetrahedroid in form, their ends triangular, their sides trapezoidal, arranged at equal and opposite

2
angles to each other and so that the ends of each figure abut upon the sides of adjacent figures, contiguous ends of adjacent figures at right angles to each other being merged.

- 5 4. A crushing roll for sugar cane mills having upon its surface figures tetrahedroid in form, their ends triangular, their sides trapezoidal, arranged at equal and opposite angles to each other, contiguous ends of adjacent figures at right angles to each other being merged.
- 10 5. A crushing roll for sugar cane mills having upon its surface figures tetrahedroid in form, their ends triangular,

their sides trapezoidal, arranged at equal and opposite angles to each other, contiguous ends of some adjacent figures at right angles to each other being merged.

In testimony whereof we have signed our names to this 15 specification, in the presence of two subscribing witnesses.

HUGH WALLACE AITKEN.
WILLIAM MACKIE.
